August A. Herring,

UNITED STATES PATENT OFFICE.

AUGUST A. HERRING, OF TOLEDO, OHIO.

HAT-FASTENER.

1,158,213.

Specification of Letters Patent.

Patented Oct. 26, 1915.

Application filed June 13, 1913. Serial No. 773,510.

To all whom it may concern:

Be it known that I, AUGUST A. HERRING, a citizen of the United States, residing at Toledo, in the county of Lucas and State of Ohio, have invented certain new and useful 5 Improvements in Hat-Fasteners, of which the following is a specification.

This invention relates to hat fasteners and more particularly to the type of hat fasteners which are permanently carried by the 10 hat.

An object of this invention is the provision of a hat fastener to be used generally with ladies' hats, which will securely hold 15 the hat upon the head by engaging the hair of the wearer and which will not shorten the longevity of the hat by performing the same in innumerable places as is commonly the case with ordinary hat pins.

20 With the foregoing and other objects in view, this invention relates to such novel features of construction, combination and arrangements of parts as will be herein-after more fully described, illustrated in 25 the drawings and claimed.

In describing the invention in detail, reference will be had to the drawings wherein like reference characters designate corresponding parts throughout the several views 30 and in which,

Figure 1 is an end view of the improved hat fastener, Fig. 2 is a sectional view through a portion of the hat fastener, Fig. 3 is a cross sectional view through a portion 35 of the hat fastener showing the manner of connecting the hair-engaging means to the handle or head of the hat fastener, and, Fig. 4 is a side elevation of the hat fastener showing parts thereof in cross section.

40 Referring more particularly to the drawings, numeral 1 designates a thin metallic plate which is secured to the wall of the hat crown by any suitable fastening means which are inserted through openings 2 in 45 the plate. The plate 1 is placed upon the interior of the hat, contacting with the inner surface of the side of the hat and carries a housing member 3 provided with a flange abutting the inner surface of the plate 1, as 50 is clearly shown in Fig. 4 of the drawings. The member 3 is substantially semi-circular in shape, extends outwardly a short distance from the surface of the plate 1 and has a flat spring 4 seated in a compartment 5 55 formed on the interior of the housing 3. The member 3 is held in engagement with

the plate 1 by means of rivets or other suitable fastening means 6.

The flat spring 4 has its end 7 wound about a pin 8 which is securely seated in 60 one of the upper corners of the compartment 5, and passes about the inner surface of the flange of the housing 3, having its free end 9 engaging an offset 10 carried by a pin 10.

The pin 10 is rotatably journaled in an 65 opening 11 extending through the plate 1 and also in an opening 12 in the upper portion of the housing 3 and has its inner end which extends within the hat curved downwardly and upwardly, being eccentrically 70 shaped as is clearly shown in Figs. 1 and 4 of the drawings.

The portion of the pin 10 which extends beyond the plate 1 and out through the hat to the exterior of the same has screw threads 75 13 formed upon its extreme outer end. The screw threads 13 form means for attaching an ornamental head 14 to the end of the pin 10. The ornamental head 14 serves as a handle portion for the turning or operating 80 of the pin 10 and also adds to the attractiveness of the device.

The inner curved end of the pin 10 is mounted within the hat so that the pointed curved portion of the same will pass through 85 the lining of the hat during the operation of the same. This feature will prevent hair from clinging to the pin 10 and also prevent the pin 10 from pulling the hair of the wearer.

When it is desired to fasten a hat upon the head of the wearer the curved portion of the pin 10 is moved so as to assume a position similar to that shown in Fig. 1 of the drawings, or having the pointed end 15 of the 90 pin 10 extending upwardly. When the hat has been properly placed upon the head the pin 10 is moved by means of the ornamental head 14 in the direction of the arrow *a*, which causes the curved portion of the pin 10 to engage the hair of the wearer. By the 95 curved portion of the pin 10 engaging the hair, the hat is firmly and securely held in its proper position upon the head of the wearer.

When it is desired to remove the hat from the head of the wearer the pin 10 is rotated in direction opposite to that indicated by the arrow *a* and the curved portion of the same moves out of the hair and allows the 100 hat to be removed.

Any number of fasteners such as has been

described and shown may be used in connection with a hat.

In practical fields certain minor features of construction may necessitate alterations 5 to which the patentee is entitled provided such alterations are comprehended within the scope of what is claimed.

What is claimed is:

1. A securing device of the character described comprising an attaching member, a housing carried by said attaching member, a pin passing through said housing and attaching member and being rotatably mounted, an offset carried by said pin in said housing, a leaf spring mounted in said housing and engaging said offset to releasably hold said pin in an adjusted position.
2. A securing device of the character described comprising an attaching means and 20 a housing, an engaging member passing through said housing and being rotatably mounted, an offset carried by said engag-

ing member, and resilient means engaging said offset for yieldably holding said engaging member in an adjusted position.

3. A securing device of the character described including an attaching member, a housing carried by said attaching member, a pin passing through said housing and said attaching member and rotatably mounted 30 therein, a head at one extremity of said pin, the opposite extremity of said pin being curved, an intermediate offset formed on said pin within said housing, and means within said housing to normally engage said offset in yieldably maintaining said pin in either one of two adjusted positions.

In testimony whereof I affix my signature in presence of two witnesses.

AUGUST A. HERRING.
